UNITED STATES PATENT OFFICE.

WILLIAM LEWIS, OF UTICA, NEW YORK.

SPRING MATTRESS.

Application filed April 26, 1927. Serial No. 186,688.

This invention relates to a spring mattress but more particularly to bed springs of the helical spring type in which the springs are arranged in upright positions in parallel 5 lengthwise rows spaced uniform distances apart and also in transverse parallel rows with uniform spaces between them.

It is well-known that in spring mattresses of this character as generally constructed 10 there is always more or less tendency of the upper helices to sag or become permanently depressed along the longitudinal center after a relatively short period of use and the main object of the present invention is to provide 15 means for effectively resisting this tendency or, in other words, to assist in maintaining all portions of the upper surface of the mattress in substantially the same horizontal plane in addition to the objects set forth in my pend- 20 ing application Serial No. 99,261, filed April 2, 1926.

In this type of mattress the major helical springs are of uniform height and are supported upon a lower deck while the intermediate 25 portions are held against relative lateral movement by an intermediate floating deck some distance from the lower and upper ends of the springs and yieldingly supported by the underlying portions thereof while at 30 the same time constituting a support for the overlying portions of the springs and one of the specific objects is to interpose additional relatively short helical springs between the lower intermediate decks so as to alternate 35 with the major springs along one of the intermediate or central rows.

Other objects and uses relating to specific parts of the mattress will be brought out in the following description.

40 In the drawings:

Figure 1 is a top plan, partly broken away, of a bed spring mattress embodying the various features of my invention.

Figure 2 is an enlarged longitudinal sectional view taken on line 2—2, Figure 1, portions of the mattress being broken away.

Figure 3 is an enlarged transverse vertical sectional view, partly broken away, taken on line 3—3, Figure 1.

50 As illustrated, this mattress comprises a

lower deck frame—1—consisting of series of cross bars—2—arranged in horizontal parallel spaced relation and having their opposite ends bent or extended upwardly at—3—above the plane of the remaining portions 55 thereof and secured to opposite side lengthwise rails—4—which are also parallel and determine the width of the mattress.

These cross bars are additionally held in fixed spaced relation by a central lengthwise 60 bar which is also disposed in a horizontal plane parallel with and midway between the side rails—4—and at right angles to the cross bars—2—and preferably consisting of sections—5—arranged end to end and having 65 their opposite ends riveted or otherwise rigidly secured to the adjacent cross bars—2—as shown more clearly in Figure 2.

These cross bars—2—and lengthwise bar 70—5—are preferably made of sheet metal strips of uniform width, the major portions of the cross bars—2—between the up-turned ends—3—being disposed edgewise vertically while the lengthwise bar sections—5—between the cross bars are preferably arranged 75 flatwise horizontally in a horizontal plane slightly above the upper edges of the cross bars.

A set of major helical springs—6—are mounted at their lower ends upon the lower 80 deck—2—to extend upwardly therefrom to approximately the same height, said spring being preferably arranged along and directly over the cross bars—2—to form parallel lengthwise rows and also parallel transverse 85 rows in sufficiently spaced relation to avoid contact one with the other.

The central lengthwise bar sections—5—form a part of the lower deck to assist in carrying out the main object of the invention or 90 more specifically to support a separate set of relatively short supplemental helical springs—7—alternating with the major springs—6—of the corresponding row in equally spaced relation thereto and in longitudinal 95 alignment therewith, said supplemental springs having their lower ends secured to the central portions of the lengthwise bar sections—5—to extend upwardly therefrom slightly less than half the height of the ma- 100

for springs —6— for a purpose hereinafter described.

The lower helices of the major springs —6— rest upon the upper edges of the cross bars —2— and are held in operative position by lengthwise wires —8— extending through the lower helices of the major springs and also around the undersides of the cross bars —2— as shown in Figures 2 and 3.

10 The lower helices of the supplemental springs —7— are passed through suitable loops —9— on the underlying portions of the central lengthwise bar sections —5—, said loops being struck up from the bar sections —5— and serve to hold the lower ends of the supplemental spring against lateral displacement relatively thereto.

An intermediate horizontal or floating deck —10— is mounted upon the upper ends of the supplemental springs —7— in normally spaced parallel relation to the lower deck —1— and is also operatively connected to the intermediate helices of the major springs —6— in such manner that the intermediate deck will be partially supported by the portions of the major springs between the lower and intermediate decks while the remaining portions of the major springs will extend upwardly from said intermediate deck.

30 This intermediate deck preferably comprises a series of lengthwise bars —11— one for each lengthwise row of the major springs —6— and each extending between adjacent intermediate helices of the major springs across the axis thereof, and a plurality of cross bars —12— arranged in parallel spaced relation across and at right angles to the lengthwise bars —11— and secured at the crossings by any suitable fastening means.

40 It is preferable to use an even number of major springs —6— in each lengthwise row and to arrange the cross bars —12— in uniformly spaced parallel relation midway between adjacent transverse rows of the major springs and, therefore, across the upper ends of the corresponding supplemental springs —7—.

The opposite ends of the lengthwise bars —11— of the floating deck —10— extend beyond the adjacent helices of the transverse end rows of springs —6— and are connected by additional cross bars —13— to assist the intermediate cross bars in holding the lengthwise bars —11— in spaced parallel relation and in stiffening the floating deck —10— as a whole, it being understood that the lengthwise bars —11— and cross bars —12— are rigidly secured to each other at their crossings by any suitable fastening means such as spot welding.

50 As previously stated the major springs —6— extend upwardly some distance above the intermediate deck —10— and the upper ends of the helices of adjacent rows are connected by horizontal diagonally extending coiled

springs —14—, Figure 1, while the upper ends of the outer lengthwise and transverse rows of the springs —6— serve to receive and support an upper deck consisting in this instance of a marginal frame preferably of heavy wire —15— extending entirely around the upper ends of the entire series of springs in about the same horizontal plane as the upper helices thereof and connected to the outer edges of said upper helices by clips —16—, Figure 2, 75 so that pressure applied to any particular portion of the marginal frame —15— will be distributed to practically all of the springs along the corresponding side or end of the mattress and to adjacent intermediate springs thereby reducing the liability of permanent deformation or sagging of those portions of the mattress which are most frequently used.

In order to further overcome the liability of permanent sagging of portions of the marginal edges of the mattress the opposite ends of the cross bars —12— of the intermediate deck are connected by braces —17— to the adjacent portions of the marginal frame —15— which also serve to transmit loads upon the marginal frame —15— to the intermediate deck —12— and thence through the underlying portions of the major springs —6— to the lower deck —1—.

Additional coiled springs —18— are interposed between the upper outer ends of the braces —17— and inwardly projecting ledges —19— on the adjacent portions of the side rails —4— to further resist the downward depression and deformation of the outer portions of the upper deck frame —15— to assist in restoring said frame to its horizontal plane when pressure thereon is removed.

The particular feature of the present invention, however, lies in the use of the relatively short supplemental springs —7— between the longitudinal center of the intermediate deck —10— and the underlying portion of the lower deck —1— in combination with the operative connection of the marginal edges of the intermediate deck with the intermediate portions of the major springs —6— for the purpose of preventing the sagging of the surface of the mattress from the marginal edges toward the center particularly when unequal weights are applied to said surface at opposite sides of the longitudinal center in which case the relatively short springs —7— tend to prevent excessive depression of the longitudinal center of the surface of the mattress while at the same time affording a high degree of resiliency, not only between the upper and intermediate decks but also between the intermediate and lower decks where the spring resistance, particularly at the longitudinal center, is somewhat greater than from the longitudinal center toward the sides.

That is, the portions of the major springs —6— above the intermediate deck are quite resilient and easily compressible under light 130

loads upon the upper deck but as these loads increase the increased resistance of the upper portions of the springs is gradually transmitted to the lower portions of said springs and to the relatively shorter supplemental spring —7—, all of which together with the said additional side springs —18— contribute to the maintenance of a uniform level of the upper surface of the mattress.

It will also be observed that any pressure applied to any portion of the upper deck or upper ends of the major springs —5— will first be transmitted to the upper portions of said springs and thence to the intermediate deck —10— which in turn will transmit the excess load to the underlying portions of the major springs —6— and also to the central row of supplemental springs —7— which latter owing to their increased resistance to the depression of the central portion of the mattress below the lower deck greatly reduces the liability of sagging of the central portion of the upper deck below the longitudinal edges thereof thereby carrying out the main object of the invention.

What I claim is:—

In a spring mattress, a lower deck, an upper deck, an odd number of lengthwise rows 30 of coiled springs supported upon the lower deck and supporting the upper deck, an intermediate deck partially supported by said springs, and relatively short coiled springs interposed between the lower and intermediate decks in alignment with the center row of the first named springs.

In witness whereof I have hereunto set my hand this 21st day of April 1927.

WILLIAM LEWIS.
